UNITED STATES PATENT OFFICE.

JAMES OBLEIN AND HENRY OBLEIN, OF LYNN, MASSACHUSETTS.

PUZZLE-BANK.

1,029,820.

Specification of Letters Patent. Patented June 18, 1912.

Application filed December 12, 1911. Serial No. 665,327.

To all whom it may concern:

Be it known that we, JAMES OBLEIN and HENRY OBLEIN, subjects of the King of Great Britain, residing at Lynn, in the 5 county of Essex and State of Massachusetts, have invented certain new and useful Improvements in Puzzle-Banks, of which the following is a specification.

This invention relates to an article having 10 parts to be locked together, such as a puzzle bank in which the cover, door or removable part is held in locked position with respect to the body, and the invention refers to a novel combination lock of a type in which 15 one or more freely movable independent bolts, or a plurality of interlocking bolts, or a combination of free interlocking spring-pressed bolts, are employed to hold the cover or door in closed position, and which are 20 capable of gravitating to or from locking position by the tilting of the bank or other article as a whole, or by the tilting of the bank and the relative movement of the parts thereof, and hence by a series of tilting 25 movements carried out in a predetermined order alone, or in connection with one or more turning movements of the bolt carrying part with respect to a locking member with which the bolts engage, the bolts can 30 be successively retracted to unlocking position for permitting the cover to be removed.

The invention has for one of its objects 35 to provide a bank or other puzzle of neat and attractive design, comparatively inexpensive to manufacture, and embodying locking means of such a nature that the bank cannot be opened except by one knowing the combination of movements to be followed out to retract the bolts of the lock.

40 Another object of the invention is the provision of a simple, effective and novel locking means which does not depend upon the use of a key but merely the following out of a certain succession of movements of the 45 part carrying the bolts so that the latter can be moved to unlocking position, the movement of the bolts to locking position being effected by a tilting movement, however slight, of the part on which the bolts are 50 mounted.

Another object of the invention is the provision of a bank having a rotary cover mounted in its top and carrying the combination lock which may be either at the top 55 of the body of the bank immediately under the cover or close to the bottom thereof,

there being in the latter form a bolt supporting disk or carrier which forms the bottom of the coin-receiving compartment of the bank.

With these objects in view and others, as will appear as the description proceeds, the invention comprises the various novel features of construction and arrangement of parts which will be more fully described 60 hereinafter and set forth with particularity in the claims appended hereto.

In the accompanying drawings, which illustrate one embodiment of the invention, Figure 1 is a perspective view of the bank. 70 Fig. 2 is a perspective view of the cover with its attached parts removed from the casing of the bank, the bolt-carrying disk being shown in dotted lines to reveal the relation of the locking bolts. Fig. 3 is a 75 central vertical section of the bank with the cover locked therein. Fig. 4 is a horizontal section taken immediately below the bolt-carrying disk or bottom of the coin compartment and showing the bolts in that position 80 where the combination of tilting movements are given to unlock the device. Figs. 5, 6, 7, 8, 9 and 10 are sectional views showing the successive steps through which the bolt-carrying part is moved to move the bolts to 85 unlocking position. Fig. 11 is an enlarged sectional view of one of the bolts and guide sleeves therefor. Fig. 12 is a side view partially in section of another form of bank. Fig. 13 is a sectional view on line 13—13, 90 Fig. 12. Figs. 14 to 20, inclusive, are similar views showing the successive steps or movements necessary to unlock the cover of the bank. Fig. 21 is a view of the adjustable baffle or key. Fig. 22 is a further modification of the locking mechanism. Figs. 23 and 24 are views of another modification. Figs. 25 and 26 are horizontal and vertical sections, respectively, of another form where- 95 in the bolts are carried by the body. 100

Similar reference characters are employed to designate corresponding parts throughout the views.

The invention is shown in the present instance as embodied in a puzzle bank, but it is 105 to be understood that the invention can be applied to any other article where the locking together of two parts or elements is desired.

The bank shown in Figs. 1 to 12, inclu- 110 sive, comprises a body A which is preferably, although not necessarily, a cylinder having

a closed bottom 1 and an open top to which is fitted a cover B that is in the present instance of such diameter as to fit within the body A, although this disposition of the 5 cover is not essential, just so a complete closure is effected to prevent coins from being extracted from the body of the bank. On one element of the bank, preferably the body, is arranged an annular flange or 10 equivalent means 2 with which the bolts of the combination lock are adapted to engage for locking the cover in closed position, and this flange is preferably, although not necessarily, disposed close to the bottom 1 but 15 spaced therefrom a sufficient distance as to accommodate the locking bolts. The locking mechanism C comprises a plurality of bolts 3 that are carried by the cover either directly or indirectly; directly when the 20 bolt-engaging member 2 is disposed at the upper portion of the cylinder A, but indirectly when the part 2 is adjacent the bottom of the cylinder. Specifically the bolts are mounted on a carrier in the form of a 25 disk 4 rigidly secured to a central stem 5 which is fastened to and extends downwardly from the center of the cover B, the disk being of such diameter that its peripheral portion will overlie and rest on the internal annular flange 2, so that in fact the 30 cover B and attached parts are supported by such flange. The bolts 3 are approximately radially disposed under and parallel with the disk 4 and are each mounted in a sleeve 35 or tubular holder 6 rigidly secured to the bottom surface of the disk 4. As shown in Fig. 11, the central portion of each bolt is formed with a central stem 7 and enlarged heads 8', and a portion 9' of the sleeve is 40 pressed inwardly to form a key that engages between the shoulders formed by the heads, so that the bolts cannot slip out of the sleeves when the cover B and locking mechanism are bodily removed from the casing A. There may be different arrangements and numbers of bolts to carry out the 45 object of the invention, but the arrangement shown in the present instance comprises two groups of bolts c and c' and two single bolts c² and c³. The bolts of each group are parallel with each other and those of one group are at right angles to the bolts of the other group. The single bolt c² is diametrically 50 opposite the group of bolts c, while the single bolt c³ is diametrically opposite the bolts c'. When the bolts are in locking position, 55 their outer ends project out of the sleeves or holders 6 and engage under the flange 2. It is not necessary for all the bolts to be simultaneously in projected position or engage 60 under the flange 2, as merely one bolt in projected position will hold the parts locked together. Under the flange are baffles 8, 9 and 10, with which the projected bolts are 65 adapted to engage so as to obstruct the turn-

ing movement of the cover with the locking mechanism and thus render difficult the relative movement of the parts to the initial position for beginning the combination of movements necessary to be carried out for 70 unlocking the bank. The baffle or projection 8 has its inner face flush with the internal edge of the flange 2, whereas the baffles or projections 9 and 10 are shorter. There can be any arrangement and member 75 of baffles but what is shown in the drawings is preferred. The projection 8 forms a bolt stop or catch for holding one of the bolts in fully retracted position during certain stages in the combination of unlocking movements, as will be now fully explained. 80

In unlocking the bank, the cover which is equipped with a handle or knob 11 must be turned back and forth while the bank as a whole is tilted in different directions until 85 a position is reached where the bolt c³ will be in line with and engaging the bolt catch or stop 8, as shown in Fig. 4. With the bank now in an upright position; that is to say, with its axis vertical, as when the bottom of the bank rests on the table, the bank is tilted forwardly so that the bolts c' opposite the retracted bolt c³ will slide inwardly until the outer ends of the bolts pass from under the flange 2, and occupy the position shown in Fig. 5. The bank is then tilted back to a vertical position and next tilted to the right so that the bolts c will slide inwardly as indicated in Fig. 6. With the two groups of bolts thus retracted, the 90 knob 11 is turned to such a position that the bolt c² will be close to the bolt catch or stop 8, as represented in Fig. 7, this turning being done while the bank is held with its axis vertical, and next the bank is tilted 95 rearwardly so that the bolt c² will slide inwardly and the bolts c will slide outwardly, as indicated, Fig. 8. It will be observed that the turning of the cover and attached parts from the position shown in 100 Fig. 6 to that shown in Fig. 7 can be accomplished without the baffles 9 and 10 interfering, the bolts nearest to such baffles being indrawn or retracted. While the bolts 105 occupy the position shown in Fig. 8, the cover and attached parts are turned far enough to bring the retracted bolt c² into line with the bolt catch or stop 8, and thus while the parts are as indicated in Fig. 12, the bank is tilted forwardly to again 110 retract the bolts c from under the flange 2, so that all the bolts will be retracted, as indicated in Fig. 10, thus permitting the cover B to be lifted out. It will be observed that the rotary movement that has been given 115 to the cover and its locking mechanism is about ninety degrees, so that the initially retracted bolt c³ never occupies a position where it can slide outwardly during the 120 steps represented by Figs. 6 to 10, inclusive. 125 130

In returning the cover, it is necessary that all the bolts remain in unlocking position or fully retracted in their respective sleeves. With the body A of the bank held vertically, the cover B held by the knob and carrying the locking mechanism is lowered vertically into the open top of the body A until the disk 4 rests on the flange 2, and a slight tilting of the bank in any direction will cause one or more bolts to slide outwardly and engage under the locking flange 2. To facilitate the sequential movements to be carried out, the cover B may be provided with suitably designated marks or divisions and a corresponding arrangement of designated marks or divisions will be arranged on the body of the bank A. The bolts are so arranged with respect to the bolt catch or stop 8 that 14 on the cover will be opposite 1 of the body to begin the initial unlocking movement. The cover and body will remain in this relative position during the necessary movements for retracting the two pairs of bolts *c* and *c'*. Then the cover B is turned so that 2 thereon will be opposite 2 on the body, when the bolts will be in the position shown in Fig. 7. After the following tilting movement to retract the bolt *c*², the cover is again turned so that 1 thereon will be opposite 1 on the body, the bolts in this position being shown in Fig. 9. These two short turning movements are the only ones necessary in the combination for the particular arrangement of bolts herein shown. By arranging the numbers on the cover and body in different relative positions, a large variety of combinations can be obtained.

As has been hereinbefore intimated, different numbers or combinations of bolts may be employed as the locking means. For instance, bolts *c* alone can be used with the bolt *c*³; or bolts *c'* with bolt *c*³; or bolt *c*² with bolt *c*³. In fact, only a single bolt may be employed, but it will be obvious that the more bolts employed, the more difficult will be the unlocking of the device. While the bolts are shown as carried by the cover element, it is obvious that they may be mounted on the body element of the bank and adapted to engage the cover element, but the operation will be practically the same as with the arrangement shown.

For the insertion of coins, the cover B has a coin slot *b* that is yieldingly closed by helical spring guards *b'* fastened to the under side of the cover, said guards preventing the extraction of the coins.

In another form of the invention, as shown in Figs. 12 to 21, inclusive, the bolts may be arranged in one or more interlocking pairs so that each pair of bolts must be moved in a predetermined order to both locking and unlocking position, thus rendering the opening of the bank more difficult, and further

more these interlocking bolts may be combined with free bolts or with spring-pressed bolts or a combination thereof. Another feature of the construction shown in Fig. 12 is the fitting of the cover or top to the bank in such a way that it is impossible for the cover to be pried open or access otherwise had to the contents of the bank. The body A' has an internal pocket at its top formed by a cylindrical flange 20 suitably secured at its lower edge to the body A', the space between the flange and body forming a pocket for receiving the annular depending rim or flange 21 on the cover 22. The cover is inserted or removed by a relatively axial movement, and on the cover is the usual knob or equivalent device 23. The bolt-engaging flange 24 is arranged at the top of the body and may be carried by the cylindrical wall 20 of the cover rim receiving pocket, and the bolts are arranged in sleeves or equivalent carriers 25 fastened to the under side of the cover. This flange 24 is provided with a circular row of spaced openings 26, each large enough to receive a screw 27 for fastening the baffles thereto. Concentric with the row of openings 26 is a row of smaller openings 29 adapted to receive a dowel pin 30 of the baffle 31, as shown in Fig. 21, such baffle having a tapped opening 32 for receiving the screw 27. The baffle 31 is the bolt catch or key baffle, as it is arranged with its bolt-engaging portion flush with the inner circular edge of the flange 24, but shorter baffles such as 33, Fig. 13, may be employed and the shorter baffles are secured in place by screws 27 also. There are three pairs of locking bolts shown, such as 34, 34^a; 35, 35^a; 36, 36^a; and also free or independent bolts 37 and 38 and a spring-pressed bolt 39. The bolts 34^a, 35^a and 36^a have their inner ends formed with heads 40, and the coacting bolts 34, 35 and 36 are formed with pins 41 that coöperate with the heads of their companion bolts. By means of these heads and pins, the bolts must be moved in a predetermined order in order to unlock the cover, as will now be described. Assuming that the cover is locked and the bolts are in the position shown in Fig. 13, and it is desired to remove the cover; the bank as a whole is tilted so that the top will move to the left, thereby throwing out the bolts 34 and 35^a, as shown in Fig. 14, the free bolt 38 being in engagement with the key baffle 31. The bank is next tilted backwardly so that the bolt 34^a will slide inwardly to the position shown in Fig. 15, and following this movement, the bank is tilted to the right so as to throw in the bolts 34 and 35^a, thereby engaging the pin of the bolt 34 with the head of the bolt 34^a and also throwing the headed end of the bolt 35^a into line with the bolt 35, as shown in Fig. 16. The bank is next tilted forwardly in order to cause the bolts 35 and 36^a 130

to slip inwardly to the position shown in Fig. 17, and while the three pairs of bolts are thus in retracted position, the cover with the attached parts is given a quarter turn to engage the bolt 34 with the key baffle 31, as shown in Fig. 18, and now by tilting the bank forwardly, the bolts 36 and 37 slide inwardly from the position shown in Fig. 18 to that shown in Fig. 19. By this time, all the interlocking bolts are unlocked and in retracted position and the free bolts are also in retracted position, the spring-pressed bolt being the only one projected. The cover is now turned until the spring-pressed bolt 39 is brought into engagement with and pressed inwardly by the key baffle 31, as shown in Fig. 20. The bolts are now all retracted so that the cover can be lifted off. The key baffle 31, by reason of the plurality of openings 26 and 29, can be placed at any desired position on the bolt-engaging flange 24 and consequently a large variety of combinations can be obtained. The bank and cover will have the combination numbers like the arrangement shown in Fig. 1, for instance.

In Fig. 22 is shown a combination of a plurality of free or independent bolts and a single spring-pressed bolt, the combination necessitating a plurality of key baffles 42 and 43 so arranged that two free bolts can be held retracted, or the spring-pressed bolt and one free bolt at the same time. Assuming that the bolts are in locking position and it is desired to unlock the cover, the cover is turned to such a position that the bolts 44 and 45 are engaged with the key baffles 42 and 43, respectively. The bank is now tilted in such a manner that the bolts 46, 47, 48 and 49 are moved inwardly successively, and then by turning the cover so that the bolts 48 and 49 will engage the baffles 42 and 43, respectively, the bolts 50 and 51 can be thrown inwardly by tilting the bank in the proper direction. The bolts being now all retracted, the cover can be removed.

Another arrangement of interlocking bolts is shown in Fig. 23, wherein one bolt 52 has its inner end formed frusto-conical like the head of a wood screw, and the other bolt 53 that interlocks therewith is arranged with its axis at an obtuse angle to the axis of the bolt 52. A free independent bolt 54 may be used in this combination and still a key baffle is unnecessary. Obstructing or interfering baffles 55 may be used to prevent free rotation of the cover within prescribed limits when the bolts are projected to locking position. On the plate 56 that carries the bolts is a lug or catch 57 which engages under the flange 58 so that it is necessary to throw the lug or catch 57 into alignment with a recess 59 in the flange 58 before the plate 56, which may correspond to the plate 4, Fig. 3, can be lifted out even though the bolts be in retracted position. To unlock

the bank with the arrangement of bolts shown in Fig. 23, the bank is tilted in such a position that the bolt 53 will be in projected position, so that its inner end will not interfere with the retraction of the bolt 52. The bank is now tilted to throw the bolt 52 inwardly to the position shown and then the bank is tilted to throw the bolt 53 inwardly where its inner end will engage behind the head of the bolt 52. Now the bank is tilted in a direction to retract the bolt 54, and during this tilting, the bolts 52 and 53 cannot slide outwardly because of their being interlocked. The cover and plate 56 are now turned to cause the catch 57 to register with the slot 59, in which position the cover and attached parts can be removed.

It has been stated hereinbefore that the bolts can be carried by the body of the bank instead of being located on the cover, as in the forms heretofore described, and this will be evident by reference to Figs. 25 and 26, wherein the bolts 60, 61, 62, 63, 64, 65, are mounted in sleeves 66 carried by the flange 67 that corresponds to the flange 24 in Fig. 12. On the cover is a disk or equivalent member 68 with which the bolts engage, this member being of such diameter as to freely enter the opening defined by the flange 67. On this plate 68 are arranged key and obstruction baffles 69 and 70, respectively, for the same purpose as the baffles heretofore described. To unlock the cover when the bolts are in locking position, the cover is turned to such a position that the bolt 60 will be engaged with the key baffle 69. The bank is now tilted so that the bolts 63 and 64 will slide outwardly beyond the edge of the plate 68. The cover is now turned so that the key baffle 69 will engage the bolt 64 and then by suitably tilting the bank the bolts 61 and 62 will slide outwardly to unlocking position. The cover is again moved to cause the spring-pressed bolt to be pressed outwardly by the key baffle 69, thus permitting the cover to be lifted off.

It is possible to so arrange the locking bolts that the bank can be unlocked without being tilted, and one of the many arrangements of bolts that will unlock without tilting of the bank is shown in Fig. 23. To unlock the bolts, the bank will be held with its axis horizontal and the bolt 54 at the top, while the bolts 52 and 53 are in projected or locking position. The bank as a unit is given a complete revolution in such a direction that the bolt 52 will be thrown inwardly first and then the bolt 53, and during this revolution the bolt 54 will also be moved inwardly. While the bolts are all in unlocking position, the body of the bank alone is turned, while the bolt-carrying part is held stationary, and as soon as the lug 57 registers with the slot 59, the cover of the bank can be removed.

- From the foregoing description, taken in connection with the accompanying drawings, the advantages of the construction and of the method of operation will be readily apparent to those skilled in the art to which the invention appertains, and while we have described the principle of operation of the invention, together with the apparatus which we now consider to be the best embodiment thereof, we desire to have it understood that the apparatus shown is merely illustrative, and that such changes may be made when desired as are within the scope of the claims appended hereto.
- Having thus described the invention, what we claim as new, is:—
1. An article comprising a body element and a cover element relatively movable while locked together, one element carrying a bolt 70
  2. An article comprising a body element and a cover element relatively movable while locked together, one element carrying a bolt 75
  3. An article comprising relatively movable body and cover elements, a bolt-engaging means on one element, and a plurality of bolts on the other element and movable into and out of engagement with said means, one bolt being movable gravitationally by the tilting of the article.
  4. An article comprising a body element and a cover element relatively movable, a bolt on one element and normally spring-pressed to locking position, a member on the other element with which the bolt interlocks in a manner to permit relative movement of the elements while they are locked together, and a key baffle with which the bolt is engaged to be thrown to unlocking position for permitting the elements to be unlocked.
  5. An article comprising a body element and a cover element relatively movable, a bolt on one element and normally spring-pressed to locking position, a member on the other element with which the bolt interlocks in a manner to permit relative movement of the elements while they are locked together, a key baffle with which the bolt is engaged to be thrown to unlocking position for permitting the elements to be unlocked, and a sliding bolt on the bolt-carrying element to gravitate into and out of locking engagement with the said member by the tilting of the body.
  6. The combination of a body element and a cover element relatively movable, with a

- lock for holding the elements together, said lock including a bolt movable on one element, a fixed locking member on the other element and with which the bolt movably engages, and a device located on the member-bearing element and in the path of the bolt whereby the device can engage the bolt and hold the same in unlocking position for permitting the elements to be separated.
7. An article comprising two elements to be locked together and relatively movable so as to be unlocked, a pair of bolts on one element movable to and from locking position by the tilting of the article, means on the other element with which the bolts engage for locking the elements together, and a device on the means-carrying element for holding one bolt in unlocking position while the article is tilted to cause the other bolt to move to unlocking position.
8. An article comprising relatively movable body and cover elements, a bolt-engaging means on one element, a bolt carrying means on the other element, a plurality of bolts movable by gravity into and out of engagement with said first means by the tilting of the article, and baffles against which the bolts strike when in locking position as the elements are relatively moved.
9. An article comprising relatively movable body and cover elements, a bolt-engaging means on one element, a bolt carrying means on the other element, a plurality of bolts on the carrying means movable by gravity into and out of engagement with said first means by the tilting of the article, and adjustable baffles against which the bolts strike when in locking position as the elements are relatively moved, one baffle being arranged to engage with and hold one bolt in unlocking position while another bolt is moved to unlocking position by the tilting of the article.
10. An article comprising a body element and a cover element relatively rotatable, and a lock for holding the elements together, said lock embodying an annular locking member or flange on the body member, a bolt on the cover element, and a baffle located in the path of the bolt to compel the article to be tilted for the bolt to pass the baffle.
11. An article comprising a body element and a cover element relatively rotatable, a plurality of bolts on one element movable to and from locking position by the tilting of the article, and a plurality of baffles located on the other element in the path of the bolts to compel tilting of the article in different directions for permitting the bolts to pass the baffles, one baffle serving to hold one bolt in unlocking position while another bolt is moved to unlocking position by the tilting of the article.
12. An article comprising a body element

and a cover element relatively rotatable, and a locking mechanism consisting of an annular flange on the body element, a plurality of radially disposed sliding bolts 5 movable inwardly and outwardly by the tilting of the article, and a plurality of baffles located under the flange to obstruct free relative rotation of the elements, one baffle having a face flush with the inner edge 10 of the flange to hold one bolt in unlocking position while the article is tilted to move other bolts to unlocking position.

13. An article comprising separable elements, and interlocking bolts on one element 15 gravitationally movable in a definite order into and out of locking engagement with the other element.

14. An article comprising separable elements, interlocking bolts on one element 20 gravitationally movable in a definite order into and out of locking engagement with the other element, and a free bolt on one element movable into and out of engagement with the other element.

25. 15. An article comprising separable elements, a pair of interlocking bolts on one element gravitationally movable in a definite order into and out of locking engagement with the other element, and a third 30 bolt movable independently of the interlocking bolts and carried by the same element to engage and disengage the other element.

16. An article comprising separable elements, interlocking bolts on one element 35 gravitationally movable in a definite order into and out of locking engagement with the other element, a spring-pressed bolt on one element normally engaging the other element, and means for holding the spring- 40 pressed bolt in unlocking position when the interlocking bolts are in unlocking position to permit the element to be detached.

17. An article comprising separable elements, interlocking bolts on one element 45 gravitationally movable in a definite order into and out of locking engagement with the other element, a freely movable bolt mounted on one element to engage the other and independent of the action of the interlocking bolts, a spring-pressed bolt mounted 50 on one element to engage the other, and means with which the spring-pressed bolt is adapted to engage so as to be moved to unlocking position while the other bolts are in 55 unlocking position to permit the elements to be separated.

18. An article comprising separable elements, and gravitationally actuated locking bolts arranged on one element in such relation that adjacent ends of the bolts interlock to compel locking and unlocking movements in a predetermined order, the other ends being adapted to engage or disengage the other element.

65. 19. An article comprising separable ele-

ments, and slidable bolts disposed at an angle to each other and having interlocking ends compelling successive movements of the bolts to and from locking position in a predetermined sequence.

20. An article comprising separable elements, a pair of bolts so arranged on one element that one extremity of one bolt will interlock with one extremity of the other bolt, and a member on the other element for 70 engagement by the other extremities of the bolts.

21. An article comprising separable elements, and bolts for locking the elements together, one bolt having a head with which 80 the other bolt is adapted to engage to compel successive movements of the bolts to and from locking position in a predetermined order.

22. An article comprising separable elements, carriers on one element, a locking member on the other element, and bolts in the carriers slidable longitudinally whereby one end of each bolt can engage the locking member and the opposite ends can engage each other to compel movement of the bolts in a predetermined order to disengage 90 the said member.

23. An article comprising body and cover elements relatively movable while locked together, a bolt-engaged member on one element, and gravitationally locked and unlocked bolts so relatively disposed on the other element as to disengage the said member in a predetermined order.

24. An article comprising elements relatively movable, a bolt engaged member on one element, and interlocking gravitationally movable bolts on the other element and arranged to engage and disengage the said 100 member.

25. An article comprising separable members relatively movable while locked, a member on one element, bolt means on the other element movably engaging the member, and an adjustable baffle associated with the member.

26. An article comprising separable members, relatively movable while locked, a member on one element, bolt means on the other element movably engaging the member, and a plurality of baffles adjustably carried by said member, one baffle having a portion flush with the edge of the member to form a bolt unlocking key.

27. An article comprising separable elements, a bolt engaged member on one element having spaced dowel and fastener openings, a baffle having a dowel to engage in any dowel opening, a fastener passing 125 through the appropriate fastener opening for securing the baffle to the member, and bolt means on the other element to engage with the said member and baffle.

28. An article comprising a cover element 130

having a depending rim, a body element having an internal pocket for receiving the rim of the cover, a member on the body element, and gravitationally actuated bolt means carried by the cover element to engage the said member to lock the elements together.

29. An article comprising a cover having an annular depending rim, a body having an annular pocket to receive the rim, an annular flange on and extending inwardly from the pocket, and gravitationally actuated bolt means on the cover for interlocking with the said flange.
- 10 30. An article comprising a body section, a cover section, and a locking mechanism including a plurality of sleeves and bolts freely slidable in the respective sleeves.

31. An article comprising elements adapted to be locked together, and a locking mechanism including a sleeve and a bolt slidable therein and having spaced shoulders, a portion of the sleeve being pressed inwardly to extend between said shoulders for retaining the bolt on the sleeve.

32. In a device of the class described, the combination with a body portion, of a cover portion mounted for rotation thereon, a plurality of bolt-carrying sleeves carried by the cover, a plurality of bolts loosely mounted in the said sleeves, a spring-pressed bolt carried by the cover, a lug having a working face, a ring carried by the body portion and beneath which the said lug lies, said lug extending to the inner periphery of the said ring, and an additional lug located beneath said ring and shorter than the first-men-

tioned lug, all of said lugs being carried by the body portion.

33. In a device of the character described, the combination with a body portion, of a cover portion mounted for rotation thereon, a plurality of bolt-carrying sleeves carried by the cover, a plurality of bolts loosely mounted in said sleeves, a spring-pressed bolt carried by the cover, a lug having a working face, a ring carried by the body and beneath which said lug lies, said lug extending to the inner periphery of the ring, and additional lugs located beneath said ring and shorter than the first-mentioned lug, said additional lugs and first-mentioned lug being equally spaced around the said ring and carried by the said body portion.

34. In a device of the character described, the combination with a body portion, of a cover portion mounted for rotation thereon, a plurality of bolt sleeves carried by the cover, a plurality of bolts loosely mounted in the sleeves, a spring-pressed bolt mounted in one of the bolt sleeves of the cover, a lug having a working face, a ring carried by the body portion and beneath which the said lug lies, said lug extending to the inner periphery of said ring, and additional lugs located beneath said ring and shorter than the first-named lug.

In testimony whereof we affix our signatures in presence of two witnesses.

JAMES OBLEIN.
HENRY OBLEIN.
